UNITED STATES PATENT OFFICE.

WILFRED GEORGE COLES, OF MADISON, WISCONSIN, ASSIGNOR TO MADISON KIPP CORPORATION, OF MADISON, WISCONSIN, A CORPORATION OF WISCONSIN.

LUBRICATOR.

Application filed April 14, 1924. Serial No. 706,589.

This invention pertains to force feed lubricators and more particularly to that type wherein a reciprocating pump element, having an oscillating movement about its axis, 5 is employed to draw in a charge of oil and then force such indrawn charge to the part to be lubricated, the pump element being oscillated to bring the intake and discharge ports or passages formed therein into registry, successively, with the intake and discharge ports formed in the cylinder or casting.

Heretofore lubricators of this type have had the ports or passages in the piston in the shape of grooves formed exteriorly thereof, and while such devices have given general satisfaction in actual practice, it has been found that where the lubricator is working against high pressure the oil is apt to be forced back through the grooves and around the piston thus minimizing the effectiveness of the apparatus at such time as its full effective capacity is needed.

Such a structure is set forth in Letters 25 Patent No. 1,262,979 to Putnam, dated April 16, 1918, and as will be seen upon reference to said patent and more particularly to Figs. 5 and 6 there is a relatively small lap between the grooves 30 and 31 and their 30 respective intake and discharge ports 32 and 33.

In actual practice it has been found that to produce a lap of suitable dimensions it is necessary to increase the diameter of the 35 plunger and the cylinder, thereby increasing the amount of oil pumped by the unit beyond a desirable quantity.

In other words, the lap can be increased indefinitely but the larger the diameter of the plunger, with any given plunger stroke, the greater the amount of oil the pumping unit will pump, and therefore, the less desirable becomes the design. Furthermore, the use of external grooves on the plunger or piston is done away with and simple cross-drillings are employed, a point of material advantage.

This invention is illustrated in the annexed drawings, wherein:

50 Fig. 1 is a vertical sectional view of a lubricator unit, the parts being shown in position at the completion of the suction stroke;

55 Fig. 2 is a horizontal sectional view on the line II—II of Fig. 1;

Fig. 3 is a view similar to Fig. 1 with the parts in position at the completion of the discharge stroke;

Fig. 4 is a horizontal sectional view on the line IV—IV of Fig. 3;

60 Fig. 5 is a sectional view illustrating the position of the reciprocating cylinder at midway of its rotation between the intake and discharge ports;

Fig. 6 is a detail perspective view, partly broken away, of the cylinder; and

Fig. 7 is a perspective view of the fixed piston or displacement member which operates with the reciprocating cylinder.

Referring first to Figs. 1 to 7, 1 denotes 70 a portion of a reservoir or casing adapted to hold the oil supply, to the side wall of which, adjacent the lower portion, is fixed a casting denoted generally by 2. Said casting is provided with a bore or opening 3, 75 which extends therethrough, the lower end whereof is threaded while the upper major part is given a true smooth finish.

A cylinder 4 is mounted for reciprocation and oscillation within the bore, such compound movement being effected through a wobbling eccentric 5, secured upon a driven shaft 6, and a yoke 7, having a gimbal joint connection with the upper end of the piston. Such means of effecting movement of the piston is disclosed in the patent aforesaid, and in Patent No. 1,066,238, to which reference is also made.

80 Cylinder 4 is provided with an axial bore or chamber 8, extending inwardly from its lower end and with two lateral bores or ports 9 and 10, which terminate at their inner ends in the upper portion of bore 8.

85 Port 9, which may be designated the intake port, is designed to be brought into registry during the intake or suction stroke with an intake or feed passage 11, while port 10 is designed to register with a discharge port or passage 12 during the forcing or displacement stroke of the cylinder, said latter port being in communication with a pipe 13 which leads to the part to be lubricated.

100 Secured within the lower threaded portion of the cylindrical bore 3 is a plug 14 to which is secured by a screw plug 15, a 105 fixed stem or piston 16, the latter being of such size as to make a close sliding fit with the bore 8 in the lower portion of the cylinder. Said piston 16 is of such height that it extends up near to but does not close up,

the ports 9 and 10 when the cylinder 4 is in its lowermost position, as illustrated in Fig. 3 and in effect forms an abutment against or upon which the indrawn oil rests prior to its being forced outwardly.

A relief port 17 is provided in the casting 2, below the lower end of cylinder 4, so as to prevent oil from being tapped below the cylinder.

10 In operation, motion being imparted to shaft 6 causes, say first an upward movement of cylinder 4, the port 9 being at such time in registry with port 11 and port 10, see Fig. 2, out of alignment with port 12. 15 Upward movement of the cylinder causes oil to be drawn in through ports 11 and 9 and into the interior of the cylinder above the fixed piston 16. Further rotation of the shaft causes the eccentric to move the cylinder about its axis, thus moving the ports 9 and 11 out of register, see Fig. 5, at which time it will be noted that there is maintained the maximum of lap which prevents the back pressure from forcing the oil backward from the interior of the cylinder through port 9, around the cylinder and out of port 11. A continued counter-clockwise 20 rotative movement of the cylinder brings the ports into registry as in Fig. 3 and Fig. 4, 25 at which time rotative movement ceases and the eccentric moves the piston downward, forcing the oil within the cylinder above the upper end of the fixed piston or abutment 16 outwardly and into pipe 13. Continued rotation of the eccentric first rotates the cylinder clockwise, to bring the ports into the 30 position shown in Fig. 3, and finally to the position in Figs. 1 and 2, whereupon the up- 35 stroke, above described, again takes place to draw in a measured charge of oil.

40 The amount of oil drawn in, and consequently the capacity of the pump, can be determined and varied by changing the bore of the cylinder 4, and making the fixed piston larger or smaller, as the case may be, to fit the same.

Such change in the pump capacity does not, however, change the degree of lap between the ports, and consequently the pump 50 remains tight, this being due to the fact that the external dimensions of the cylinder is not diminished.

Under the construction above described, the piston 16, by reason of the way it is mounted, will center itself in the bore of the cylinder without difficulty.

What is claimed is:

1. In a force feed lubricator the combination of a pump casting having oppositely disposed inlet and exhaust ports opening into a cylindrical bore formed in said casting; a cylinder mounted for endwise movement and oscillation about its axis in said bore, said cylinder having laterally extending inlet and exhaust ports passing through

the wall thereof and opening into the space within said cylinder, said ports standing at an angle to each other; stationary means cooperating with the lower portion of the cylinder to force an in-drawn charge of oil upwardly therein and out through the exhaust ports; and means serving to reciprocate the cylinder and to oscillate the same about its axis.

2. In a force feed lubricator the combination of a pump casting having oppositely disposed inlet and exhaust ports opening into a cylindrical bore formed in said casting; a cylinder mounted for endwise movement and oscillation about its axis in said bore, 75 said cylinder having laterally extending inlet and exhaust ports passing through the wall thereof and opening into the space within said cylindrical bore, said ports standing at an angle to each other; a fixed 80 abutment cooperating with the lower portion of the cylinder bore to force an in-drawn charge of oil upwardly therein and out through the exhaust ports; and means serving to reciprocate the cylinder and to oscillate 85 the same about its axis.

3. In a force feed lubricator the combination of a pump casting having oppositely disposed inlet and exhaust ports opening into a cylindrical bore formed in said casting; a cylinder mounted for endwise movement and oscillation about its axis in said bore, said cylinder having laterally extending inlet and exhaust ports passing through the wall thereof and opening into the space 95 within said cylinder, said ports standing at an angle to each other; a fixed piston mounted in the lower portion of the casting and extending upwardly into the bore of the cylinder; and means serving to reciprocate the 100 cylinder and to oscillate the same about its axis.

4. In a force feed lubricator the combination of a pump casting having oppositely disposed inlet and exhaust ports opening into a cylindrical bore formed in said casting; a cylinder mounted for endwise movement and oscillation about its axis in said bore, said cylinder having laterally extending inlet and exhaust ports passing through the wall thereof and opening into the space 110 within said cylinder, said ports standing at an angle to each other; a fixed piston extending into the lower end of said cylinder; a mounting engaging the lower end of said piston, said mounting being secured within the lower end of the cylindrical bore formed in the casting; and means serving to reciprocate the cylinder and to oscillate the same 115 about its axis.

5. In a force feed lubricator the combination of a pump casting having oppositely disposed inlet and exhaust ports opening into a cylindrical bore formed in said casting; a cylinder mounted for endwise move- 120

ment and oscillation about its axis in said bore, said cylinder having laterally extending inlet and exhaust ports passing through the wall thereof and opening into the space within said cylinder, said ports standing at an angle to each other; a plug screw threaded into the lower portion of the cylindrical bore aforesaid, said plug being interiorly threaded; a piston having an enlarged lower

end, the upper end of the piston passing into the lower end of the cylinder; and a threaded plug screwed into the threaded bore of the first mentioned plug; and means serving to reciprocate the cylinder and to oscillate the same about its axis.

In testimony whereof I have signed my name to this specification.

WILFRED GEORGE COLES.
